UNITED STATES PATENT OFFICE.

CHARLES EDGAR NORTHRUP, DECEASED, LATE OF ORION, MICHIGAN; BY CLARA L. NORTHRUP, ADMINISTRATRIX, OF ORION, MICHIGAN.

LOCK.

Application filed January 26, 1924. Serial No. 688,820.

To all whom it may concern:

Be it known that I, CLARA L. NORTHRUP, a citizen of the United States, and a resident of Orion, in the county of Oakland and State of Michigan, administratrix of the estate of CHARLES EDGAR NORTHRUP, deceased, late a citizen of the United States, and late a resident of Orion, in the county of Oakland and State of Michigan (as by reference to the duly certified copy of letters of administration will more fully appear), who did in his lifetime invent a new and Improved Lock, do declare the following is a full, clear, and exact description.

This invention relates to locks and has for an object to provide an improved construction wherein a plurality of differently actuated tumblers are provided.

Another object is to provide a lock of the tumbler type in which there is provided a key operated series of tumblers and a pawl operated series of tumblers.

A still further object of the invention is to provide a lock of the tumbler type in which a plurality of differently operated tumblers are provided and a locking pin associated with one set of tumblers whereby an exact fitting key must be provided to answer the requirements of the different series of locking means.

In the accompanying drawing—

Figure 1 is a longitudinal vertical sectional view through a lock embodying the invention, the same being shown in a locked position with a key partially inserted.

Figure 2 is a sectional view through Figure 1, approximately on line 2—2.

Figure 3 is a view similar to Figure 2 but showing the key inserted to a great extent.

Figure 4 is a view similar to Figure 3 but showing the key fully inserted and the locking tumblers and other mechanism moved to an unlocked position.

Figure 5 is a front elevation of the lock shown in Figure 1 with a covering plate partially broken away.

Figure 6 is a sectional view through Figure 1, approximately on line 6—6.

Referring to the accompanying drawing by numerals, 1 indicates a barrel and 2 a cylinder rotatably mounted in the barrel 1. The barrel 1 may be connected to a door or other device in any desired manner and the squared member 3 may be connected to the

bolt in any suitable manner, said squared member being pivotally connected to the cylinder by a suitable pin 4. In forming the bore in the barrel 1 for receiving the cylinder 2, an arc-shaped groove 5 is also provided, said groove being of some appreciable width for purposes hereinafter fully described. The cylinder 2 is also provided with an annular groove 6 accommodating the pin 7 mounted in any desired manner in the barrel 1 whereby the cylinder may freely rotate but cannot be moved longitudinally.

In forming the barrel 1, suitable apertures are provided for the various tumbler structures 8 and 9 and also a suitable key slot 10 is provided for receiving the key 11. The key slot 10 is provided with a sleeve 12 having an enlarged end 13 covering the end of the cylinder 2 and also forlapping somewhat part of the barrel 1. The sleeve 12 is provided with a passage-way for receiving the key 11 and also a cut-out portion or slot 14 registering with the cut-out portion 15 in the cylinder 2.

From Figure 2 it will be noted that the cut-out portion 15 merges into the opening adapted to receive the tumblers 9. These tumblers, as well as tumblers 8, are of the usual construction and are spring pressed so that normally their connecting members will be out of line with the surface of the cylinder 2 so as to prevent rotation thereof. As these members are of ordinary construction, it is thought no further description will be necessary.

As indicated in Figure 1, the tumblers 8 are operated by the raised portion 16 whereby they are properly moved to permit the cylinder to rotate. In order to cause the tumblers 9 to move to an inoperative position, a pawl or dog 17 is provided pivotally connected at 18 to the key 11. This pawl is provided with a rounded hook-shaped portion 19 merging into an end 20 and also provided with a tail section 21 which has a rounded back designed to engage the lower section of tumbler 9 and raise said tumbler as indicated in Figure 4. When the key is pushed inwardly from the position shown in Figure 2, the rounded hook portion 17 will strike against the respective shoulders 22 and 23 of the sleeve 12 and will be swung around so that the end 20 will strike the end of the pin 24 and will force said pin back against the action of spring 25 as the

key is moved to the position shown in Figure 4. The pin 24 is provided with a projecting lug 26 which normally fits in the end of slot 27, which slot or groove extends longitudinally of the barrel 1. When the pin 24 is moved back to the position shown in Figure 4, the lug 26 will be brought opposite, or rather into, the arc-shaped groove 5 whereby the cylinder 2 may be freely rotated as the lug 26 will not stop such movement and as the respective tumblers 8 and 9 are already moved to an inoperative position. It will be noted that the projection 16 operates one set of tumblers while the pawl or dog 17 operates the other set of tumblers and the pin 24. As the parts are made to fit properly and also as the parts are small, it will be necessary not only to make the projection 16 of a proper height to shift the tumblers 8 but it will also be necessary to mount the pawl 17 in correct position and make this pawl of the proper length.

In view of the accuracy in which pawl 17 is to be mounted, it will be difficult to duplicate a key even when provided with a proper key as a guide and, consequently, it will be impossible to use a substitute key. It will also be noted that by reason of the structure set forth, ordinary picking tools cannot be used as the pin 24 could not be operated thereby.

What is claimed is:—

1. A lock and key comprising a barrel, a rotatable cylinder arranged in said barrel, a plurality of tumblers projecting from the barrel into the cylinder, a pin carried by the cylinder and projecting into the barrel, and a key formed with means for simultaneously moving said pin and tumblers to an inoperative position whereby the cylinder may be rotated.

2. In a lock of the character described, a barrel, a cylinder rotatably mounted in the barrel, a tumbler structure for connecting the barrel and cylinder, a pin for connecting the barrel and cylinder, and a key provided with a pivotally mounted pawl formed with oppositely acting ends constructed to move the tumbler structure and the pin to inoperative positions when the key is fully inserted whereby said cylinder may be rotated.

3. In a lock of the character described, a lock structure and key, said key being formed substantially flat with a raised portion, said key being also provided with a notch and a pawl pivotally mounted therein, said pawl having its pivotal mounting intermediate the ends whereby there are provided opposite working ends, said lock being formed with a slot for receiving said key and with a plurality of locking tum-

bler structures adapted to move to inoperative positions by said pawl and by said 65 raised portion.

4. The combination with a lock having a casing, a rotatable barrel positioned in the casing, a tumbler structure normally locking said barrel against rotation, of a key 70 therefor comprising a flat body having a raised portion and an opening, a pawl normally arranged in said opening, and a pivoted pin extending through said pawl intermediate the ends, said ends acting to 75 operate said tumbler structures when the key is in use.

5. In a lock, a barrel having a bore extending entirely therethrough, a cylinder rotatably mounted in said bore, means for 80 preventing longitudinal movement of said cylinder, said cylinder being provided with a key slot, a sleeve arranged in said key slot formed with a passage-way for receiving a key, said sleeve having an enlarged end covering the end of said cylinder and overlapping part of the barrel, means for connecting said sleeve to said cylinder, and means for normally preventing rotation of said cylinder, said means being adapted to 90 be moved to an inoperative position by a key whereby the cylinder may be freely rotated.

6. In a lock of the character described, a barrel having a bore extending therethrough 95 and an arc-shaped groove and a longitudinally arranged positioning groove intersecting the arc-shaped groove, a cylinder rotatably mounted in the bore, a pin mounted to reciprocate in said cylinder, said pin being formed with a projection adapted to normally fit into said longitudinal groove, and a key formed with means for moving said pin so that the enlargement thereof will be in said arc-shaped groove when the key 100 is fully inserted whereby said cylinder may be rotated.

7. In a lock of the character described, a barrel, a cylinder rotatably mounted in the barrel, said barrel being provided with a 110 longitudinally extending groove and an arc-shaped groove intersecting with the longitudinally extending groove, a spring pressed reciprocating pin carried by the cylinder and formed with a projection normally fitting into the longitudinally extending groove for locking the barrel and cylinder together, said pin being adapted to be moved against the action of said spring for causing said enlargement to be positioned in said arc-shaped groove whereby the cylinder may be 120 freely rotated.

CLARA L. NORTHRUP,
*Administratrix of the Estate of Charles E.
Northrop, Deceased,*
